UNITED STATES PATENT OFFICE.

RICHARD KRAUSE, OF NEW YORK, N. Y.

DESIGN FOR TRIMMING.

SPECIFICATION forming part of Design No. 16,859 dated August 17, 1886.

Application filed July 3, 1886. Serial No. 207,148. Term of patent 31 years.

To all whom it may concern:

Be it known that I, RICHARD KRAUSE, of the city, county, and State of New York, have invented a new and original Design for Trimmings, of which the following is a specification.

The nature of my design is fully represented in the accompanying drawing, to which reference is made.

10 This design relates to dress-trimmings made of ruching.

The leading feature of my design consists in a ruching ornamented by spirally-conical projections.

15 In the drawing, A represents the ruching; B, plaits or folds in the same; C, conical

spiral projections on the ruching between the folds or plaits, and D the plaited backs.

Having thus described my design, I claim as new and desire to secure by Letters Patent—

The design for ruching, substantially as herein shown and described, consisting of ruching and spiral conical projections on the same.

In testimony that I claim the foregoing as my invention I have signed my name in presence of two subscribing witnesses.

RICHARD KRAUSE.

Witnesses:
